COMBINATION BUS AND RAILROAD COMMUTER CAR

John R. Cooney, Dyer, Ind., assignor to Pullman
Incorporated, a corporation of Delaware

Filed Aug. 29, 1961, Ser. No. 66,536

Term of patent 14 years

(Cl. D66—1)

FIG. 1 is a perspective view of a combination bus and railroad commuter car showing my new design;

FIG. 2 is an elevational view of the side opposite that shown in FIG. 1; and

FIG. 3 is an exploded perspective view thereof.

The end of the car not shown in FIG. 1 is substantially the same as the one shown.

The essential features of my design reside in the portions shown in full lines.

I claim:

The ornamental design for a combination bus and railroad commuter car, substantially as shown and described.
